CLAIM

We claim the ornamental design for a wireless access point, as shown and described.

DESCRIPTION

FIG. 1 is a front perspective view of a wireless access point showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

(Continued)

The broken lines in the figures depict environmental subject matter and form no part of the claimed design.

1 Claim, 4 Drawing Sheets
